(57) CLAIM

The ornamental design for a board game, as shown and described.

DESCRIPTION

FIG. 1 is a front, right, top perspective view of a board game, showing my new design;

FIG. 2 is a rear, left, bottom perspective view of a board game, showing my new design;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 3;

FIG. 11 is an enlarged view of detail 11 in FIG. 5;

FIG. 12 is an enlarged view of detail 12 in FIG. 6;

FIG. 13 is an enlarged view of detail 13 in FIG. 7;

FIG. 14 is an enlarged view of detail 14 in FIG. 8;

FIG. 15 is an enlarged view of detail 15 in FIG. 8;

FIG. 16 is a front, right, top perspective view of the board game in an alternate configuration;

FIG. 17 is an enlarged view of detail 17 in FIG. 16;

FIG. 18 is an enlarged view of detail 18 in FIG. 16; and,

FIG. 19 is an enlarged view of detail 19 in FIG. 16.

The dashed broken lines in the figures are for the purpose of illustrating portions of the board game that form no part of the claimed design. The dash-dot-dot-dash lines depicting the boundary of the board game form no part of the claimed design. The dot-dash lines shown in FIGS. 1, 3, 5, 6, 7, 8 and 9-19 are for the purpose of disclosing areas of enlargement that form no part of the claimed design.

1 Claim, 19 Drawing Sheets
